LEWIS T. WILCOX, OF PEEKSKILL, NEW YORK.

LIQUID-FUEL STOVE.

1,409,631.

Specification of Letters Patent. Patented Mar. 14, 1922.

Application filed February 10, 1920. Serial No. 357,613.

To all whom it may concern:

Be it known that I, LEWIS T. WILCOX, a citizen of the United States, residing at Peekskill, in the county of Westchester, State of New York, have invented an Improvement in Liquid-Fuel Stoves, of which the following is a specification.

My invention relates to oil burners of the kind usually employed in oil cooking and other stoves.

In burners of this kind, it is common practice to provide a horizontal oil supply pipe communicating with a suitable reservoir, and to mount the burners on this pipe and supply them with oil by tapping the pipe at each burner. In this arrangement the burners are supported on the oil supply pipe which in turn is supported in the frame of the stove, and the connection between the supply pipe and the burner is made in various ways for the purpose of supporting or bracing the wick trough, which in turn supports the other parts of the burner.

Many difficulties have been encountered in using this construction, and many devices have been designed to overcome these difficulties. One of the problems which presents itself is that of making a simple, strong and effective connection between the oil-supply pipe and the pipe communicating between it and the burner trough, which will resist and maintain its position under strains of all kinds and which may be quickly and easily made and adjusted without the use of soldering or similar operations. It is to provide an efficient device of this character that the present improvements are primarily designed.

The improvements are illustrated in the accompanying drawings referred to herein, and in which Figure 1 is a vertical longitudinal section of a supply pipe, burner trough and connection taken medially thereof, with the portion of the supply pipe in elevation.

Fig. 2 is a plan of the parts shown in Fig. 1.

Fig. 3 is a partial vertical transverse section of the yoke for clamping the burner to the supply pipe.

Fig. 4 is an elevation of the portion of the connecting device which is fixed to the burner trough or wick holder.

Fig. 5 is a detail in perspective of the oil supply pipe and tap.

Figs. 6 and 7 are a side elevation and a

plan respectively of a modified form of connection.

Figs. 8 and 9 are details of modified forms of the parts shown in Fig. 4, the former showing the said part in elevation and the latter the pipe with a conical seat therein, and

Fig. 10 is an elevation of the connection showing the same with a threaded end.

A simple and effective arrangement of burner and supply pipe is that shown in Fig. 1, in which a burner member, or wick shell or holder 10, sometimes called the burner trough, is placed on the horizontal oil supply pipe 11 in such a manner that the said pipe extends diametrically across its bottom, and the connecting member 12 is secured to the wick holder on the outside thereof and to the supply pipe immediately below it. In view of the fact that this is the only support of the wick holder, combustion tubes mounted thereon and other parts it is important that the connection shall be very strong and secure and capable of holding the parts in proper position under all the ordinary conditions and strains of use. The items of simplicity and economy are also important ones, and the simplification of such parts as are used is therefore desirable. The present improvements meet these requirements.

In carrying out the present improvements the supply pipe 11 is indented or countersunk as shown at 13, and provided with a small flat table 14, and then tapped at the bottom of the indentation as shown at 15 to receive the angular end 16 of the connection 12, secured to the wick holder 10 by means of the integral flange plate 17 by having rivets 18 or other suitable fastenings passed through openings 19 in the plate and through the outer wall of the holder. Communication between the wick holder and the supply pipe is established through the channel 20. The connection 12 has a shoulder 21, and between this shoulder and the pipe a gasket 22 of compressible material is located. In making the parts the pipe is first grooved or indented. This may be done by placing it in a grooved die and subjecting it to the action of a punch. The aperture to receive the part 16 is then drilled. In this manner the indentation is made with accuracy and the shape of the hole is not affected by the indenting operation. If desired the hole may be punched, as shown in

Fig. 9, so that the metal surrounding it will form an inwardly tapering seat, or it may be threaded as shown in Fig. 10. In the first case the end of the connection 12 will be conical as shown at 24, and in the second case it will be threaded as shown at 25.

The parts described are now placed in position, and the split loop 26 passed around the bottom of the pipe and closed over the 10 horizontal portion of the connection 12. The loop is preferably made of spring metal so that it can be spread open to permit this. This construction obviates the necessity of placing the loop on the pipe before the 15 parts are assembled, and causes it to assume its proper position. The ends of the loop 26 overlap as indicated at 27 and 28 and are provided with tapped openings 29 adapted to receive a bolt 30 which is turned down 20 therein until it bears against the top of the connection 12 immediately above the seat of the said connection. Further turning of the bolt causes its lower end to press against the said part and thus force the extremity 25 16 of the connection 12 into the opening of the pipe 11, and also compress the gasket 22. The device is now completed and ready for use. In the modification of Fig. 30 10 the strap may be dispensed with, and the threaded end 25 screwed down into the threaded opening of the supply pipe by rotating the connection and the wick holder after these parts have been connected. In 35 addition to the riveting of the plate 17 to the wick holder the connection 12 is secured thereto by having the lip extended under the bottom of said holder and united therewith.

In the modification of Figs. 6 and 7 the 40 double loop 32 is used, and the wick holder suspended from the pipe connection at the side of the supply pipe, and as in the preferred form, it is held against movement in all directions by the socket joint above described.

45 In this construction however, the bolt preferably passes freely through an opening provided therefor in the top of the loop and engages with a nut in which it turns so as to free the nut against the under surface of the top of the loop when the end of 50 the nut is turned into contact with the connecting member to secure the parts in place.

I claim as my invention:

55 1. In an apparatus of the class described, a supply pipe, a burner member, a fitting secured at one end to the said burner and adapted at its other end to directly engage an opening provided therefor in the said 60 supply pipe, and a clamp engaging the said fitting and supply pipe to make a tight joint between the same.

2. In an apparatus of the class described,

a supply pipe having a flattened face with an opening therein, a burner, a fitting secured at one end to the said burner and adapted at its other end to directly engage the said opening in the supply pipe and to bear against the said flattened face thereof, and a clamp engaging the said fitting and supply pipe to make a tight joint between the same.

3. An apparatus of the class described, a supply pipe having a flattened face and an opening centrally disposed therein, with the walls of the flattened face of substantially the same thickness as the body of the pipe, a burner, a fitting secured at one end to the said burner and at the other end being reduced to directly engage the opening in the pipe, a washer placed over the reduced end of the fitting and adapted to bear against the flattened face of the pipe, and a clamp engaging the said fitting and pipe to make a tight joint between the same.

4. An apparatus of the class described, a supply pipe having a flattened face and an opening centrally disposed therein, with the walls of the flattened face of substantially the same thickness as the body of the pipe, a burner, a fitting secured at one end to the said burner and at the other end being reduced to directly engage the opening in the pipe, a washer placed over the reduced end of the fitting and adapted to bear against the flattened face of the pipe, a clamp extending around the supply pipe and having overlapping ends extending over a portion of the said fitting, and a clamp screw passing through openings in the overlapping ends of the clamp to engage the fitting and secure the same to the said supply pipe.

5. In an apparatus of the class described, a supply pipe having a portion thereof compressed to form a flattened face in which there is an aperture, a burner member, a hollow connecting member secured to the said burner member and having a reduced end portion, a washer surrounding the reduced end of the connecting member and adapted to bear against the adjacent portion thereof and also against the said flattened face of the pipe, a clamp extending around the supply pipe and having overlapping ends extending over a portion of the hollow connecting member, and a clamp screw passing through an opening in the overlapping ends of the clamp to engage the hollow connecting member to secure the same in place relatively to the said supply pipe.

Signed by me this 31st day of January, 1920.

LEWIS T. WILCOX.
